CLAIM

We claim, the ornamental design for a spout for packaging container, as shown and described.

DESCRIPTION

FIG. 1 is a top, front, right side perspective view of a spout for packaging container, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a bottom, front, left side perspective view thereof;

FIG. 9 is a cross-sectional view taken along line 9-9 of FIG. 6;

FIG. 10 is a reference view thereof showing the claimed design in an environment in which it may be used; and, FIG. 11 is a reference view thereof showing the claimed design in another environment in which it may be used.

The broken lines in the drawings show portions of the spout for packaging container or environment that form no part of the claimed design. Surfaces shown within the broken lines do not form a part of the claimed design. Surfaces shown between broken lines and solid claim lines form a part of the claimed design.
